UNITED STATES PATENT OFFICE.

NEVIN AUGUSTUS ARCHIBALD, OF CONCORD, NORTH CAROLINA.

REIN-HOLDER.

986,890.

Specification of Letters Patent. Patented Mar. 14, 1911.

Application filed June 9, 1910. Serial No. 565,970.

To all whom it may concern:

Be it known that I, NEVIN AUGUSTUS ARCHIBALD, a citizen of the United States, residing at Concord, in the county of Cabarrus and State of North Carolina, have invented a new and useful Rein-Holder, of which the following is a specification.

It is the object of this invention to provide, in a simple, merchantable and inexpensive form, a rein holder which may readily be assembled with whip socket, or other like support, to coöperate therewith, in engaging the reins.

Another object of the invention is to provide a holder adapted to coöperate with a fixed support in engaging the reins, and to provide means whereby a single holder may be adjustably mounted upon supports of different diameters.

With the above and other objects in view, the invention consists in the novel construction and arrangement of parts hereinafter described, shown in the drawings, and specifically claimed. The drawings show but typical embodiments, and it is to be understood that changes, properly falling within the scope of what is claimed, may be made without departing from the spirit of the invention.

In the accompanying drawings, Figure 1 is a plan of the blank from which the rein holder is formed; Fig. 2 is a side elevation of a whip socket showing the rein holder of my invention mounted in place thereon; and Fig. 3 is a transverse section of the rein holder only, taken upon the line A—B of Fig. 2.

The rein holder forming the subject matter of this application, is preferably fashioned from a single blank of metal, the outline of which is seen most clearly in Fig. 1. The rein holder includes a resilient tongue 1, and oppositely disposed arms 2 and 3. There may be any number of these arms, and in the present instance, two spaced pairs of them are shown, the arms being located adjacent the lower end of the tongue 1, and formed integrally therewith. The tongue 1 may be prolonged, as shown at 4, below the lower pair of tongues 2, 3, in order to bear against a fixed support, to steady the rein holder thereon, when the device is mounted as shown in Fig. 2. In the arms 2 there are elongated slots 5; and in the arms 3 there are openings 6, preferably cir-

cular in outline. The arms 2 and 3 are flexible, so that they may be bent to encircle a fixed support, such for instance, as a whip socket 7. Retaining elements, preferably taking the form of threaded bolts 8 are mounted in the apertures 5 and 6. These retaining elements 8 are provided with heads 9, the openings 6 in the arms 3 being countersunk, for the reception of the heads. Upon the protruding ends of the retaining elements 8, clamping devices, preferably wing nuts 10 may be mounted.

It will be seen that the arms 2 and 3 may be made to encircle the whip socket 7 closely, the retaining elements 8 sliding in the elongated slots 5, to permit the necessary adjustment of the arms 2 and 3 about the whip socket. The wing nuts 10 may be tightened, and thus the tongue 1 will be held in close proximity to the whip socket 7, the tongue and the whip socket coöperating to hold the reins between them.

The edges of the tongue 1 may be made to converge adjacent the upper end of the tongue, as shown at 11, in order to facilitate the bending of the upper end of the tongue 1 away from the whip socket 7, to form a hook as denoted by the numeral 14. This bending of the tongue at 14 facilitates the introduction of the rein between the tongue and the whip socket, and the inner edge of the tongue 1 may be rounded, as shown at 12, so that the reins will not be injured when they are introduced into the grip of the hook 14, or when they are being removed therefrom, it being noted that the reins may be engaged and held between the free end of the hook and the body of the tongue 1. Moreover, this hook 14 serves as a hold, by means of which the device may be held against the whip socket 7 while the arms 2 and 3 are being engaged about the socket.

The structure herein described is a simple one, and is adapted to be mounted upon a whip socket, without the use of tools, to coöperate with the whip socket in engaging the reins. The device may be quickly mounted in place, and readily removed, the construction being such that a single rein holder is adapted to be mounted upon whip sockets or other supports, having different diameters.

Having thus described the invention, what is claimed is:—

As an article of manufacture, a blank for

the formation of a rein holder, comprising in a resilient, one piece structure, a straight tongue rounded at both ends and tapered at one, and thiere being spaced pairs of oppositely disposed arms projecting from the tongue at points remote from the tapered end thereof, the arms upon one side of the tongue having elongated slots adjacent their ends, and the arms upon the other side of

the tongue having circular openings adjacent their ends.

In testimony that I claim the foregoing as my own, I have hereto affixed my signature in the presence of two witnesses.

NEVIN AUGUSTUS ARCHIBALD.
